(57) **CLAIM**

I claim the ornamental design for a jig fishing lure, as shown and described.

DESCRIPTION

FIG. 1 depicts a jig fishing lure, with a barbed hook and jighead connected with a ring assembly;

FIG. 2 is a right side view of a jig fishing lure, with a barbed hook and jighead connected with an eye and ring assembly; FIG. 3 is a front view of a jig fishing lure, with a barbed hook and jighead with an eye and ring assembly;

FIG. 4 is a left side view of a jig fishing lure, with a barbed hook and jighead with an eye and ring assembly;

FIG. 5 is a perspective view of a jig fishing lure, with a barbed hook and jighead with an eye and ring assembly;

FIG. 6 depicts a jig fishing lure, with a barbed hook and jighead connected with a ring assembly;

FIG. 7 is a right side view of a jig fishing lure, with a barbed hook and jighead connected with an eye and ring assembly; FIG. 8 is a front view of a jig fishing lure, with a barbed hook and jighead with an eye and ring assembly;

FIG. 9 is a left side view of a jig fishing lure, with a barbed hook and jighead with an eye and ring assembly;

FIG. 10 is a perspective view of a jig fishing lure, with a barbed hook and jighead with an eye and ring assembly;

FIG. 11 depicts a jig fishing lure, with a barbed hook and jighead connected with a swivel and ring assembly;

FIG. 12 is a right side view of a jig fishing lure, with a barbed hook and jighead connected with a swivel and ring assembly; FIG. 13 is a front view of a jig fishing lure, with a barbed hook and jighead connected with a swivel and ring assembly;

FIG. 14 is a left side view of a jig fishing lure, with a barbed hook and jighead connected with a swivel and ring assembly;

FIG. 15 is a perspective view of a jig fishing lure, with a barbed hook and jighead connected with a swivel and ring assembly;

FIG. 16 depicts a jig fishing lure, with a barbed hook and jighead connected with a ring assembly;

FIG. 17 is a right side view of a jig fishing lure, with a barbed hook and jighead connected with a swivel and ring assembly;

FIG. 18 is a front view of a jig fishing lure, with a barbed hook and jighead connected with a swivel and ring assembly;

FIG. 19 is a left side view of a jig fishing lure, with a barbed hook and jighead connected with a swivel and ring assembly; and,

FIG. 20 a perspective view of a jig fishing lure, with a barbed hook and jighead connected with a swivel and ring assembly. The broken line showing of environment in the drawings is included for the purpose of illustrating only and forms no part of the claimed design.
